[57] CLAIM

The ornamental design for an electrophotographic apparatus, as shown and described.

DESCRIPTION

FIG. 1 is a front view of the electrophotographic apparatus;

FIG. 2 is a rear view thereof;

FIG. 3 is a top plan view thereof;

FIG. 4 is a bottom plan view thereof;

FIG. 5 is a side elevational view as seen from the left of FIG. 1;

FIG. 6 is a side elevational view as seen from the right of FIG. 1;

FIG. 7 is a cross sectional view without internal structures taken in the direction of the arrows as shown in FIG. 3 along lines 7—7;

FIG. 8 is a cross sectional view without internal structures taken in the direction of the arrows as shown in FIG. 3 along lines 8—8; and

FIG. 9, a perspective view wherein the electrophotographic apparatus is loaded with paper cassettes and the cover is opened.
